Dominic P. Dululio, Leominster, Mass.

Application July 22, 1950, Serial No. 11,360

Term of patent 3½ years

(Cl. D80—9)

To all whom it may concern:

Be it known that I, Dominic P. Dululio, a citizen of the United States, residing at Leominster, county of Worcester, State of Massachusetts, have invented a new, original, and ornamental Design for Combination Earring and Ring Rack, of which the following is a specification, reference being had to the accompanying drawing, forming part thereof.

Fig. 1 is a perspective view of a combination earring and ring rack showing my new design;

Fig. 2 is a top plan view thereof on a reduced scale; and

Fig. 3 is a side elevational view thereof.

I claim:

The ornamental design for a combination earring and ring rack, as shown.

DOMINIC P. DULULIO.
